[57] CLAIM

The ornamental design for a vehicle mirror with housing, as shown and described.

DESCRIPTION

FIG. 1 is a front view of a vehicle mirror with housing according to my novel design;

FIG. 2 is a left side view of a vehicle mirror with housing according to my novel design;

FIG. 3 is a right side view of a vehicle mirror with housing according to my novel design;

FIG. 4 is a rear view of a vehicle mirror with housing according to my novel design;

FIG. 5 is a top view of a vehicle mirror with housing according to my novel design;

FIG. 6 is a bottom view of a vehicle mirror with housing according to my novel design;

FIG. 7 is a perspective view from the rear right of a vehicle mirror with housing according to my novel design; and, FIG. 8 is a perspective view from the front right of a vehicle mirror with housing according to my novel design.

The broken line immediately next to the structure line represents the bounds of the design. All other broken line matter represents environment. None of the broken lines form any part of the claimed design.
